CONTINUOUS GRATING STRUCTURE

Richard J. Barry, New York, N. Y., and Clarence H. Lewis, Darien, Conn., assignors to Walter Edward Irving, Glenbrook, Conn.

Application March 14, 1944, Serial No. 526,414

7 Claims. (Cl. 189—82)

1

This invention relates to improvements in continuous grating structures, and more specifically to a splice for coupling the ends of adjacent grating panels together to form a uniform traffic-bearing grating surface over which motor vehicles and the like are adapted to travel.

Traffic-bearing grating structures of the past with which we are familiar have their ends coupled together in a manner which destroys the uniform continuity of the traffic-bearing surface of the grating structure. One cause thereof is due to the lapping of the ends of the grating panels which presents added thicknesses of grating bars at the traffic-bearing surfaces of the spliced joints between panels, such type of joint being present in the patents to Van Hoffer No. 1,629,184, dated May 17, 1927; Price No. 1,817,463, dated August 4, 1931; and our prior Patent No. 2,193,287, dated March 12, 1940. This non-uniformity in the traffic-bearing surface of the grating structure at the joints between panels of present installations imparts to the occupants of motor vehicles which pass thereover, a weaving and swaying sensation, similar to that experienced when a vehicle is about to skid. Therefore, the primary object of this invention resides in a continuous traffic-bearing grating structure in which the traction-bearing surface constructed of spliced grating panels is uniform throughout its entire length, and which avoids the conditions aforesaid.

Another feature of the invention is to provide a continuous grating structure formed of a plurality of grating panels spliced together at their adjacent ends, which enables a maximum fabrication of the panels in a shop and a minimum amount of labor on a job during construction of a traffic-bearing grating structure.

A further feature of the invention is the provision of a splice coupling between the meeting ends of traffic-bearing grating panels which is of sufficient strength to withstand the loads and stresses to which the same is subjected by heavy vehicular traffic which may pass thereover when in use.

A still further feature of the invention is to provide a splice joint between the meeting ends of two adjacent grating panels in which the meeting ends of the traffic-bearing surface of straight bars are disposed in edge to edge relation without disturbing the uniform design of the meshes formed by intermediate crimped strips.

Other novel features of the invention will become apparent as the following specification is

2

read in conjunction with the accompanying drawings, in which,

Figure 1 is a collective fragmentary top plan view of three grating panel sections in separated relation and in related position for coupling together.

Figure 2 is a fragmentary top plan view of the meeting ends of two grating panels spliced together, and a third panel connected to one side thereof and in lapped relation to the spliced joint.

Figure 3 is a side elevational view with parts broken away.

Figure 4 is an enlarged vertical sectional view on the line 4—4 of Figure 2.

Figure 5 is a detail vertical transverse sectional view on the line 5—5 of Figure 4.

Figure 6 is a detail vertical transverse sectional view on the line 6—6 of Figure 4.

Figure 7 is a fragmentary horizontal sectional view on the line 7—7 of Figure 4.

Figure 8 is a fragmentary horizontal sectional view on the line 8—8 of Figure 4.

Figure 9 is a sectional perspective view of the offset end of one of the straight bars, the dot and dash lines indicating the lapping straight bar of an adjacent panel.

Referring to the drawings by reference characters, and at present to Figures 1 and 2 of the drawings, A and B designate two traffic-bearing grating panels arranged in end to end relation and forming part of one row of panels while C designates a companion traffic-bearing grating panel forming part of a second row of like panels.

The panel C is disposed in side by side relation to the panels A and B and in lapping relation to the spliced joint therebetween. The grating panels A, B and C are of a like construction, therefore a description of one will suffice for the others.

Each traffic-bearing panel includes a plurality of spaced metal longitudinal bars, the number of said bars depending upon the width of the panel desired. The length of the bars also depends upon

the length of the panel desired, and in practice, the length and width will be such as to enable the expeditious handling of the panels during manufacture, shipment, and handling upon a job. For illustration purposes, four of such longitudinal bars have been shown and are designated 10, 11, 12 and 13. Interposed between the bars 10—11, 11—12, and 12—13 are crimped metal strips 14, 15, and 16, respectively. A similar crimped strip 17 engaging the bar 13 is also provided and constitutes one longitudinal side edge of the panel,

while the other longitudinal edge is defined by the bar 10.

The straight bars 10, 11, 12 and 13 are of the same length but their ends terminate in alternate staggered relation so that the spliced joints therebetween will be correspondingly staggered to impart additional strength thereto.

Each straight bar terminates at one end in a splicing portion 18 which is in true alignment with the major portion of the length of the bar, while the other end of each bar terminates in a straight offset splice tongue or extension 19. The tongues 19 are offset laterally in the same direction for a distance equal to the thickness of the bars of which they form an integral part. The offset of each bar is designed 20 and is formed by first coping away a portion of the top edge of the tongue 19 as at 21, slitting the bar horizontally and inwardly from the top coped edge of the tongue as at 22, and finally bending the tongue outwardly a distance equal to the thickness of the bar and in parallel relation thereto. This coping and slitting of the bar provides a shoulder abutment portion 23 adjacent and above the plane of the offset 20 which remains in alignment with the entire traffic-bearing surface of the bar and against which the end of a splicing portion 18 of a joining panel abuts.

The entire top edge of the tongue 19 is not coped for an upwardly extending lug 24 remains thereon at a point approximately midway the length of the tongue, the purpose of which will be hereafter more fully understood. The length of the lug 24 is approximately that of the flat bar contacting portion 25 of a crimped strip for serving as such when two partial mesh-forming sections of the connected panels A and B are completely spliced together.

Each crimped strip, as previously mentioned, is provided with flat equidistantly spaced bar contacting portions 25, each of which is provided with a rivet hole 26 therein. The straight bars are also provided with equidistantly spaced rivet holes 27 therein which align with the holes 26 of the crimped strips. The crimped strips are of a height less than that of the bearing bars but their top surfaces are disposed on the same horizontal plane as top surfaces of said bars. The rivet holes 27 in the bars are therefore disposed above the plane of the horizontal mid portion thereof.

The splice tongue 19 is provided with a rivet hole 28 midway between its ends and which is spaced from the adjacent last rivet hole 27 a distance equal to that between the rivet holes 27. The tongue is also provided with two additional rivet holes 29-29 which are spaced a distance from rivet hole 28 on opposite sides thereof for a distance approximately one half the distance between rivet holes 27.

The splicing portion 18 has a rivet hole 30 spaced from the adjacent rivet hole 27 a distance equal to the distance between rivet holes 27. Also, the splice portion 18 is provided with rivet holes 31-31 at spaced distance at opposite sides thereof equal to approximately one half the distance between rivet holes 27.

In fabrication of a panel in a shop, the contacting portions 25 of the crimped strips are secured to adjacent bars, except the outer side bar 10, by rivets 32 which pass through rivet holes 26 in the contacting portions 25 and which register with the holes 27 in said bars. The outer side bar 10 is connected to the contacting portions of its adjacent crimped strip by temporary fastening such as by bolt and nut means 34. As best seen

in Figure 1, the bolt and nut means may skip certain rivet holes for such means is temporary and is removed upon a job to effect a rivet coupling between the longitudinal sides of adjacent panels.

The crimped strips terminate adjacent the ends of straight bars and in alternate staggered relation in order to form a uniform mesh at the spliced joints. The ends of the crimped strips 14 and 16 at that end of the panel having the straight splice portions 18 terminate in one arm 35 of a single crimp. The arms 35 are disposed short of the portions 18. The corresponding ends of the crimped strips 15 and 17 terminate in arms 36 which also form part of a single crimp. The arms 36, however, lap a portion of the splice portions 18, and the next adjacent contacting portion 25 of the crimped strips freely engage the respective bars and have their holes 26 in register with the holes 30 for the reception of rivets when the adjacent ends of the grating panels are spliced together.

The ends of the crimped strips which terminate adjacent that end of the panel having the offset splicing tongues 19 are also alternately staggered as best illustrated in Figure 1. The outer arms 37 of the last crimp of the crimped strips 14, 15 and 16 have their ends respectively welded to the confronting sides of tongues 19 of the bars 11, 12 and 13 as at 38. The welded ends of the arms 37 abut the tongues 19 in a vertical plane at the inner ends of the lugs 24. The bar engaging portions 25a of the strips 14 and 16 terminate in spaced relation to the respective adjacent offset tongues 19 of the bars 10 and 12. The end of the strip 17 terminates in a single arm 37a having an integral bar contacting portion 25b, which is welded to the single arm 36 of the corresponding strip 17 of a meeting companion panel.

Assume that three shop fabricated grating panels such as shown at A, B and C in Figure 1 are to be placed in position upon a job to form a continuous traffic-bearing grating structure. The panels A and B are placed in a horizontal position with the offset tongues 19 of the straight bars of panel A disposed in aligned confronting relation with the splice portions 18 of the straight bars of panel B. One of the panels, A or B, is shifted relative to the other to cause the tongues 19 to assume an overlapping position with respect to the respective splice portions 18. The free ends of the portions 18 of panel B abut the shoulders 23 of panel A, although for expansion purposes the ends of the portions 18 and the shoulders may be spaced a slight distance apart. The holes 31-31 in the portions 18 register with the holes 29-29 in the tongue 19 and receive rivets 40. The holes 30 of portions 18 of panel B register with holes 28 of tongues 19 of panel A. The holes 26 of the alternate free end crimps also register with the holes 30 and 28 of related lapping bar ends and receive rivets 41. The portions 18 of bars 10 and 12 of panel B are engaged by the engaging portions 25a of strips 14 and 16 of panel A and the holes 26 therein register with the holes 28 of bars 10 and 12 of panel A and with holes 30 of bars 10 and 12 of panel B and receive rivets 41. With the spliced ends of the panels riveted together in the manner just described, the free terminal ends 35 of the strips 14 and 16 are in meeting engagement with the outer end portions of the lugs 24 of bars 11 and 13 of panel A and are welded thereto and to the outer side of the offset tongue as at 43. The terminal end 36 of strip 15 of panel B is welded at 43 to the lug 24

of bar 12 of panel A. The crimped strip 17 being a side strip has the terminal end 36 of said strip of panel B welded as at 45 to the adjacent terminal end 255 of strip 17 of panel A. The meeting ends of panels A and B are now spliced together, with the top edges of the offset tongues 18 disposed below the plane of the aligned straight bars of the panels A and B. The partial end crimps 35, 36 and 37 of the strips meet the ends of their related lugs 24 and coat therewith to form complete crimps, the top edges of which are on the same plane as the top edge surfaces of the bearing bars, thus forming uniformity of traffic-bearing surfaces at the spliced joint between panels.

The bolts 34 along bars 10 of panels A and B are replaced by rivets when the panels are placed in position upon a job.

The panel C is placed in a position in staggered relation to a splice joint between panels A and B, and the bolts 34 thereof are also removed and replaced by rivets 44 which pass through the aligned rivet holes in the bar 10, strip 14, of panel C and rivet holes 26 in the outer side crimped strip 17-17 of panels A and B. It will be understood that any number of longitudinal staggered rows of grating panels may be arranged in horizontal side by side relation, depending upon the width of the traffic-bearing structure to be laid.

From the foregoing description taken in connection with the accompanying drawings, it will be understood that there is uniform continuity throughout the continuous traffic-bearing surface of the spliced grating sections, the movement of traffic thereover being parallel to the bearing bars. There is no added thickness of bars or strips at the spliced joints between grating panels, which would tend to cause uneven travel of the wheels of a vehicle thereover, and which condition also imparts a weaving and swaying sensation to the occupants of a vehicle when passing thereover. Also, this improved splice facilitates a maximum shop fabrication of the grating panels and a minimum of welding and riveting upon the job, thus expediting handling and laying of the panels in the construction of a grating traffic-bearing structure.

While we have shown and described what we consider to be the preferred embodiment of our invention, we wish it to be understood that such changes in construction and design as come within the scope of the appended claims may be resorted to if desired without departing from the spirit of the invention.

Having thus described the invention, what we claim as new is:

1. A continuous traffic-bearing grating structure comprising in combination, a pair of like rectangular grating panels arranged in horizontal end to end relation, each of said grating panels comprising spaced straight metal bars of uniform thickness with intervening crimped metal strips having their upper edge surfaces disposed on the same plane as the upper edge surfaces of the bars, the adjacent ends of the bars of the panels being in abutting engagement and longitudinal alinement, the abutting ends of the bars of one panel each having a straight laterally offset splicing tongue integral therewith and parallel thereto, the distance of the offset being equal to the width of the bar, the upper edge of the tongue being cut away inwardly from the offset and inwardly from its free end to provide spaced-apart portions disposed below the plane of its related bar, said tongues overlapping and

engaging the respective adjacent ends of the other panel, fastening means for securing the tongues of the bars of one panel to the adjacent ends of the bars of the other panel, and means for securing the adjacent ends of the crimped strips to the respective tongues at the inner ends of the cut away portions in a manner to maintain the continuity thereof.

2. A continuous traffic-bearing grating structure comprising in combination, a pair of like rectangular grating panels arranged in horizontal end to end relation, each of said grating panels comprising spaced straight metal bars of uniform thickness with intervening crimped metal strips having their upper edge surfaces disposed on the same plane as the upper edge surfaces of the bars, the adjacent ends of the bars of the panels being in abutting engagement and longitudinal alinement, the abutting ends of the bars of one panel each having a straight laterally offset splicing tongue integral therewith and parallel thereto, the distance of the offset being equal to the width of the bar, the upper edge of the tongue being cut away inwardly from the offset portion and inwardly from the free end thereof to provide spaced apart portions which are disposed below the plane of its related bar, said tongues overlapping and engaging the respective adjacent ends of the other panel, fastening means for securing the tongues of the bars of one panel to the adjacent ends of the bars of the other panel, the upper edge of the tongue between the cut away portions constituting an upstanding lug, the adjacent terminal end portions of a pair of the corresponding strips of the two panels coating to form a crimp, said end portions being welded to an adjacent tongue at the respective ends of the lug thereof.

3. A continuous traffic-bearing grating structure comprising in combination, a pair of like rectangular grating panels arranged in end to end relation, each of said grating panels comprising spaced straight metal bars of uniform thickness with intervening crimped metal strips having their upper edge surfaces disposed on the same plane as the upper edge surfaces of the bars, the adjacent ends of the bars of the panels being in abutting engagement and longitudinal alinement, the ends of the bars of one panel each having a straight laterally offset splicing tongue integral therewith and parallel thereto, the distance of the offset being equal to the width of the bar, the upper edge of the tongue being cut away at its ends, the tongues of the bars of one panel overlapping and engaging the respective ends of the bars of the other panel, and welds fixedly securing the adjacent ends of certain of the crimped strips to the tongues at the inner ends of the cut away portions at the joint formed by the overlapping tongues and adjacent bar ends to maintain the continuity of the strips at the joints therebetween.

4. A continuous traffic-bearing grating structure comprising in combination, a pair of like grating panels arranged in end to end relation, each of said grating panels including spaced straight metal bars of uniform thickness with intervening crimped metal strips having their upper edge surfaces disposed on the same plane as the upper edge surfaces of the bars, the ends of the bars of one panel terminating in laterally offset portions defining shoulders at the inner ends thereof, the distance of the offset of each offset portion being equal to the width of the bar, the offset portions of the bars of one panel

overlapping the adjacent ends of the bars of the other panel with the shoulders thereof in confronting relation to the ends of said bars, the top edge of each of the offset portions being cut away at its ends and disposed below the plane of the overlapping end of the adjacent bar, the top edge portion of each offset portion intermediate the cut away portions constituting an upstanding lug the adjacent terminal end portions of the corresponding strips of the two panels cooperating with the lugs to form crimps, and weld joints securing the ends of the crimped strips to the adjacent bars.

5. A continuous traffic-bearing grating structure comprising in combination, a pair of like grating panels arranged in end to end relation, each of said grating panels including spaced straight metal bars of uniform thickness with intervening crimped metal strips having their upper edge surfaces disposed on the same plane as the upper edge surfaces of the bars, the ends of the bars of one panel terminating in laterally offset portions defining shoulders at the inner ends thereof, the distance of the offset of each offset portion being equal to the width of the bar, the offset portions of the bars of one panel overlapping the adjacent ends of the bars of the other panel with the shoulders thereof in confronting relation to the ends of said bars, the top edges of the offset portions being cut away at their ends and disposed below the plane of the overlapping ends of the adjacent bars, and means for securing the adjacent ends of the crimped strips to the bars at the inner ends of the cut away portions to maintain the continuity of the traffic bearing surfaces at the joint therebetween.

6. A continuous traffic-bearing grating structure comprising in combination, a pair of like grating panels arranged in end to end relation, each of said grating panels comprising a series of spaced straight metal bars of uniform thickness with intervening crimped metal strips having their upper surfaces on the same plane as the upper edge surfaces of said bars, the ends of the bars at one end of the panel constituting splicing portions, straight offset splicing tongues integral with the other ends of said bars and parallel thereto, the distance of the offset being

the same as the thickness of the bars, each of said tongues having its upper edge cut away inwardly from the offset of the tongue and inwardly from the free end thereof, the intervening portion

5. portion of the top edge of the tongue between the cut away portions constituting an upstanding lug forming part of a full crimp, the offset tongues of one grating panel overlapping the respective splicing portions of the other panel whereby the
10. straight bars of the pair of panels are in longitudinal alignment, fastening means passing transversely through the lapping tongues and splice portion, one terminal end of each crimped strip of one panel being disposed on the offset side of each adjacent bar and terminating in an arm forming a part of a crimp and being welded to the tongue at the inner end of the lug, the adjacent end of each complementary crimped strip of the other panel terminating in an arm of a crimp and meeting the outer end of the lug and being welded thereto, the upper surfaces of the arms being on the same plane as the upper surface of the lug and cooperating therewith to provide a complete crimp.
15. 7. A continuous traffic-bearing grating as set forth in claim 6 including arms forming partial crimps at the meeting ends of the crimped strips disposed on that side of the bars opposite the offset of the tongues and being welded together to provide complete crimps.

RICHARD J. BARRY.
